UNITED STATES PATENT OFFICE

PARIS R. FORMAN, OF RAHWAY, NEW JERSEY, ASSIGNOR TO NATIONAL PNEUMATIC COMPANY, OF NEW YORK, N. Y., A CORPORATION OF WEST VIRGINIA

DOOR LOCK

Application filed April 21, 1926. Serial No. 103,437.

This invention relates broadly to door locks.

One of the objects of the invention is the provision of a novel lock structure for use on the doors of vehicles, especially cars, such as are used by railways.

One of the objects of the invention is the provision of a lock adapted to be used in connection with the axle generator of vehicles.

10 One of the objects of the invention is the production of a lock which is adapted to maintain the door locked during the motion of the vehicle to which it is applied but which may be opened by means of a special key by 15 the conductor when he so desires.

A still further object of the invention is to provide a lock for vehicle doors which is adapted to be free for opening when the vehicle is at a standstill.

20 A still further object of the invention is the provision of a lock structure which is adapted to be maintained locked when the car is not in motion when this is desirable.

The invention resides substantially in the 25 construction, combination, arrangement and relative location of parts, all as will be more fully indicated in the following specification.

These and other objects, as will appear in the following description, are obtained by 30 means of the construction shown in the figures of the drawings, in which the same reference numerals will be used throughout to indicate the same or similar parts.

35 Fig. 1 shows a top plan view with some parts broken away, for purposes of illustration of my novel lock structure.

Fig. 2 shows a side elevational view of this lock.

40 Fig. 3 is a view of my lock structure as applied to the framework of a vehicle looking down on the device.

45 Fig. 4 is a diagrammatic view of the circuit arrangement of the lock in connection with the axle generator and

Fig. 5 is an enlarged detailed view showing a modification of the device.

Fig. 6 is a diagrammatic arrangement showing the use of either a battery or the axle generator and a method of controlling more than one lock at a single point.

Fig. 7 shows the same arrangement as Fig. 6, but applied to one lock magnet only.

In Fig. 1, the casing 1 and cover 5 are shown. The casing, which contains the lock structure, is shown in Fig. 3 attached to the vestibule framework of the vehicle in co-operative relation with the door 2 of the vehicle, on which is mounted the member 4 for receiving the latch bolt. This device is particularly adapted for use with doors of the cylinder type such as are found on vehicles and which are adapted to be opened before the trap door is lifted.

Within the casing 1 is shown an inlet coupling 6 to which is connected the conduit for enclosing or protecting the lead wires which are to be connected to the terminals 7 within the casing. Wires are led from these terminals to the electro-magnet 8 in the usual and well known manner. The electro-magnet 8 is mounted within the casing on a suitable bracket adjacent the support 9 forming part of the casing on which is pivoted a short armature 10 adapted to rest in its normal position against the stop 11. Mounted on a transverse shaft 12 journalled in the casing and cover is a handle 13, and keyed to the shaft within the casing is a lever 14 having a small projecting end 14'. Above the magnet 8 is mounted the rod 16 having at one end a short plate 15 and on its other end the latch bolt 17. The rod 16 slides in a bracket 16' at one end, and at the other the latch bolt 17 slides through an opening in the casing and maintains the bolt 17 extended through the casing 1. At the upper end of the casing is provided an opening 19 to receive a key which operates the short lever 18.

As is shown in Fig. 4, the electro-magnet 8

is connected in series with the axle generator 27 which is of the usual type found on the axle of each car comprising a train, and is adapted to generate electricity whenever the 5 car is in motion. Thus it will be seen that whenever the car is moving, the electro-magnet 8 will be energized and the armature 10 will rest upwardly against the core of the magnet so as to be in the path of the projection 10' on the lever 14. Thus it will be impossible to move the handle 13 to the right (Fig. 1) to withdraw the latch bolt 17. By this arrangement, it will be seen that a passenger will be unable to unlock the door of 15 the vehicle while the train is in motion. Thus by this arrangement possible injury to a passenger who might otherwise open the door will be prevented. In case the conductor should desire to open the door for any reason, 20 he may insert the proper key in the opening 19, and by rotating the lever 18 to the left, withdraw the latch bolt so that the door may be opened even though the train is in motion. It will also be evident that as soon as the train 25 comes to a standstill the armature 10 will return to its position against the stop 11 so that the handle 13 may be operated to withdraw the latch bolt.

I have shown a modification in Fig. 5 by 30 means of which it is possible to maintain the doors locked even though the train is not in motion. To the lock structure as disclosed above may be added a small cylinder 20 having mounted therein piston 21 which may 35 be forced upwardly against the action of the spring 22 when air pressure is supplied in back of the piston through the pipe 23. A small rod projecting through the casing and attached to the piston may cooperate with the 40 end of the armature 10 to force it upwardly so that the lower end of the lever 14 may not be moved to the right because it is set against a projection on the arm 10. Fluid pressure from any suitable source, either the braking 45 system, or the fluid pressure source used for supplying water to the basins in the vehicle wash rooms will be supplied by the pipe 26 to the valve 24 which in one position will supply fluid pressure to the pipe 23 and in 50 its other position may exhaust the fluid pressure from the cylinder 20 through the pipe 25. Thus it will be seen that the doors may be maintained in locked position even when the vehicle is at rest when this is desirable. 55 It is, of course, possible to apply this invention to a vehicle having both an axle generator and a battery, as shown in Figs. 6 and 7. This can be accomplished in one form by means of a double pole, double throw switch 60 adapted in one position to connect the magnet 8 to the axle generator and in the other to a battery or other current source 52. By this arrangement, the invention can be adapted to lock the doors on a vehicle, should 65 the generator go bad, or to lock the doors by

current from the battery source when the vehicle is or is not in motion, should the pneumatic means become inoperative. The lock could also be applied to vehicles which have no axle generator, such as motor buses. 70

By the arrangement in Fig. 6, the electro-magnets can be connected in parallel, as many as desired, and controlled by a single switch 51, so as to be operated either by the generator 27 or the battery 52. Thus the doors 75 may be locked when the vehicle is at rest or in motion, either by the pneumatic means or by the electro-magnetic means, using either current source.

It is evident from the foregoing description 80 that I have provided a novel lock particularly adapted for use on vehicles supplied with axle generators. I do not, however, desire to be limited to the particular embodiments of the invention shown in the drawings, but rather to the scope and spirit of my invention as defined in the appended claims. I am well aware that many changes in the details of construction and arrangement of parts may readily suggest themselves to one 85 skilled in the art. Thus, if desired, only one axle generator could be used and all the electro-magnets could be connected in series; and the single valve 24 in the modification of Fig. 5 might be arranged to control the pistons 90 associated with any number of locks. 95

Having now described my invention, what I seek to secure by United States Letters Patent is:

1. In a vehicle door safety lock the combination with a vehicle having doors thereon, of separate electrical means on each door for rendering the doors normally locked when the vehicle is in motion, and separate pneumatic means associated with each of said electrical means to lock the doors whether the vehicle is in motion or not. 100
2. In a vehicle door safety lock the combination with a vehicle having doors thereon and an axle generator, of electro-magnetic means connected to said generator for locking said doors when the vehicle is in motion, and manually controlled pneumatic means for locking the doors. 105
3. In a vehicle door safety lock the combination with a vehicle having doors thereon and an axle generator, of a bolt for normally engaging a door when closed, electro-magnetic means for preventing the movement of the bolt, said means being connected to the generator to prevent movement of the bolt when the vehicle is in motion, manual means for moving said bolt when the vehicle is in motion, and manually controlled pneumatic means for preventing the movement of said bolt whether the vehicle is stationary or not. 115
4. In a vehicle door safety lock the combination with a vehicle having doors thereon and an axle driven generator, of means connected to the generator for locking the doors 120
5. In a vehicle door safety lock the combination with a vehicle having doors thereon and an axle generator, of means connected to the generator for locking the doors 125
6. In a vehicle door safety lock the combination with a vehicle having doors thereon and an axle driven generator, of means connected to the generator for locking the doors 130

when the vehicle is in motion, manual means for operating said first mentioned means when the vehicle is stationary, said first mentioned means being rendered operative while the vehicle is in motion to lock the doors against operation by said manual means, and manually controlled pneumatic means for locking the doors when the vehicle is stationary or in motion.

10 In testimony whereof I have hereunto set my hand on this 19th day of April, A. D., 1926.

PARIS R. FORMAN.
